UNITED STATES PATENT OFFICE.

WILLIAM WAKLEY, OF INDIAN LAKE, NEW YORK.

DESIGN FOR A HARNESS-RING.

44,503.

Specification for Design.

Patented Aug. 12, 1913.

Application filed April 23, 1913. Serial No. 763,173. Term of patent 7 years.

To all whom it may concern:

Be it known that I, WILLIAM WAKLEY, a citizen of the United States, residing at Indian Lake, in the county of Hamilton and State of New York, have invented a new, original, and ornamental Design for a Harness-Ring, of which the following is a specification, reference being had to the accompanying drawing, forming part thereof.

The figure is a perspective view of a harness ring showing my new design.

I claim:

The ornamental design for a harness ring, as shown.

WILLIAM WAKLEY.

Witnesses:

GEO. RICHARDSON,
G. C. WILSON.
